[57] CLAIM

The ornamental design for a medical stand with articulating arm and monitor for imaging mammalian tissue, as shown and described.

DESCRIPTION

FIG. 1 is a perspective view of the medical stand with articulating arm and monitor for imaging mammalian tissue; FIG. 2 is a front elevational view of the medical stand with articulating arm and monitor for imaging mammalian tissue; FIG. 3 is a right elevational view of the medical stand with articulating arm and monitor for imaging mammalian tissue; FIG. 4 is a left elevational view of the medical stand with articulating arm and monitor for imaging mammalian tissue; and,

FIG. 5 is a top plan view of the medical stand with articulating arm and monitor for imaging mammalian tissue. The surfaces or portions of the article not shown in the drawing or described in the specification form no part of the claimed design.
